UNITED STATES PATENT OFFICE.

WALLACE ODELL, OF NORTH TARRYTOWN, NEW YORK.

DESIGN FOR A PUZZLE-BOARD.

SPECIFICATION forming part of Design No. 33,187, dated September 11, 1900.

Application filed August 6, 1900. Serial No. 36,099. Term of patent 7 years.

To all whom it may concern:

Be it known that I, WALLACE ODELL, a citizen of the United States, residing at North Tarrytown, in the county of Westchester and State of New York, have invented and produced a new and original Design for a Puzzle-Board, of which the following is a specification.

This invention relates to a new and original design for a puzzle-board; and it has for its object to provide a design of this character which shall be both useful and ornamental.

The leading feature of the design resides in a board provided on its playing field or surface with the representation of a human face with the teeth exposed, said playing field or surface being also provided thereon with cavities arranged at different points within the plane of the outlines of the teeth.

The minor features of the design are the board being of a circular conformation and provided with an upper smooth convexed playing field or surface and a peripheral upstanding flange projecting above the plane of the said playing field or surface.

In the drawings, Figure 1 is a plan view of a puzzle-board embodying the herein-described design. Fig. 2 is a cross-sectional view thereof.

Referring particularly to the drawings, the numeral 1 designates the puzzle-board, which is of a circular outline or configuration, the same being provided with an upstanding flange 2, encircling the periphery thereof and projecting above the plane of the top surface 3 of the board. The said board is further provided with an upper smooth convexed playing field or surface 3, which playing field or surface is provided thereon with the representation of a human face with the teeth exposed. In addition to the representation or caricature thereon the playing field or surface 3 of the board is further provided with a plurality of cavities 4 of different sizes and arranged at different points within the planes of the outlines of the teeth.

What is claimed is—

The design for a puzzle-board herein shown and described.

In testimony that I claim the foregoing as my own I have hereto affixed my signature in the presence of two witnesses.

WALLACE ODELL.
